(57) **CLAIM**

The ornamental design for a handbag as shown and described.

DESCRIPTION

FIG. 1 is a perspective view of the handbag showing my new design, the handbag shown in a closed position;

FIG. 2 is a perspective view of the handbag shown in an open position;

FIG. 3 is a front view of FIG. 1;

FIG. 4 is a back view thereof;

FIG. 5 is a left side view thereof;

FIG. 6 is a right side view thereof;

FIG. 7 is a top view thereof; and,

FIG. 8 is a bottom view thereof.

The broken lines illustrate portions of the handbag that form no part of the claimed design.

1 Claim, 8 Drawing Sheets
